(57) **CLAIM**

We claim the ornamental design for a display screen or portion thereof with animated graphical user interface, as shown and described.

DESCRIPTION

FIG. 1 is a front view of a display screen or portion thereof with animated graphical user interface showing a first image of our new design;

FIG. 2 is a second image thereof;

FIG. 3 is a third image thereof;

FIG. 4 is a fourth image thereof; and,

FIG. 5 is a fifth image thereof.

The broken lines showing an electronic devise and display screen illustrate environmental structure and the article of manufacture, respectively. The remaining broken lines illustrate portions of the graphical user interface. None of the broken lines form part of the claimed design.

The appearance of the animated images transitions between the images shown in FIGS. 1-5. The process or period in which one image transitions to another forms no part of the claimed design.
